UNITED STATES PATENT OFFICE.

WILLIAM H. PETERS, OF COLUMBUS, OHIO, ASSIGNOR, BY MESNE ASSIGNMENTS, TO THE JAEGER MACHINE COMPANY, OF COLUMBUS, OHIO, A CORPORATION OF OHIO.

MACHINE FOR MIXING MATERIALS FOR CONCRETE.

No. 864,386.

Specification of Letters Patent.

Patented Aug. 27, 1907.

Application filed November 7, 1905. Serial No. 286,223.

To all whom it may concern:

Be it known that I, WILLIAM H. PETERS, a citizen of the United States, residing at Columbus, in the county of Franklin and State of Ohio, have invented certain new and useful Improvements in Machines for Mixing Materials for Concrete; and I do hereby declare the following to be a full, clear, and exact description of the invention, such as will enable others skilled in the art to which it appertains to make and use the same.

10 The object of this invention is to provide an improved machine for mixing materials especially the components of artificial stone as for example sand and cement.

The invention consists more particularly in an improved construction of mixing and feeding device 15 hereinafter described and claimed, the invention not being confined to precisely the forms of the parts shown.

In the accompanying drawings showing one embodiment of the invention—Figure 1 is a side elevation of the machine; Fig. 2 is an elevation of the feeding end 20 of the machine with the driving pulley removed; Fig. 3 is a similar view of the discharging end; Fig. 4 is a perspective view of the mixing and feeding device; and Fig. 5 is a sectional detail illustrating the gearing for effecting the operation of the parts.

25 In the several views 1 designates the mixing drum. This drum is supported upon two idler rollers 2^a and two rollers 2 on a driven shaft 3.

The character 4 designates a hopper that is divided into two compartments provided at their lower ends 30 with feed screws on hollow shaft 5 and solid shaft 6 respectively. These screws discharge the material through openings in a stationary plate 4^a secured to the hopper.

5^a designates a driving shaft having a band pulley 35 5^a attached thereto, said shaft 5^a extending through the hollow shaft 5 and eccentrically into the drum 1, and on this shaft 5^a is a mixing and feeding device which comprises four spiders 6 corresponding to each other, each spider having four arms the arms of the opposite 40 pairs of which are at angles of about 75 degrees to each other, in which case, of course, the angle between the pairs themselves at each side would be about 105 degrees. These spiders are arranged equidistantly apart on the shaft 5^a and they are so secured to said shaft that 45 the extremity of the arm of the second spider adjacent a wide angle and the extremity of the arm of the first spider that is adjacent the smaller angle are in a straight line parallel with the axis of the shaft 5^a, and so on around, or so that when the blades are attached to the 50 extremities of the arms straight portions 16 will alternate around the shaft with inclined or spiral portions 17 between the several spiders as indicated in Fig. 4. The blades themselves will be placed flatwise against the sides of the arms of the spiders. The advantage 55 of this double alternation of the straight with inclined

or spiral portions is that the materials to be mixed will not only be more thoroughly agitated but they will at the same time be fed through the cylinder.

The shaft 6^a is provided with a disk 7 having concentric circles of face gear teeth 7^a, 7^b, 7^c, and 7^d. 60 Journaled on the frame across the toothed side of the disk 7 is a shaft 8 connected with which so as to be slidable thereon but rotatable therewith is a pinion 9. The pinion 9 can be slid or adjusted to engage any of the concentric rows of teeth 7^a, &c., and it is held from 65 movement when adjusted by means of a fork 10 having its shank bolted to the appropriate one of a series of holes 11^a in a bar on the frame 11.

On the hollow shaft 5 is a gear 12 having rim teeth 12^a and miter face teeth 12^b. The rim teeth 12^a engage an 70 intermediate pinion 13 that in turn drives the gear 14 on the shaft 3. The shaft of the intermediate pinion 13 also contains a spur gear 15 that is driven by a pinion 5^b on the shaft 5^a. The miter face gear 12^b engages a miter gear 8^a on the shaft 8. 75

By shifting the sliding pinion 9 from one circle of face teeth on the disk 7 to another the ratio of the speeds of the shafts 5 and 6^a can be varied and consequently the quantities of the components of the mixture correspondingly varied.

80 By the arrangement of gearing shown the drum and bladed mixing device thereon are driven in contrary directions.

From the above description and from the drawings it will be observed that the blades are arranged in a 85 circular series about the shaft with the adjacent blades of the series at an angle to each other, or with the alternate blades parallel and the intermediate blades at an angle to the parallel blades. It will also be seen that the drum turns with a comparatively slow motion 90 while the bladed mixing and feeding device turns with a rapid motion in close proximity to the side of the drum. In operation, therefore, the materials to be mixed are carried with a slow motion by the bottom of the drum up to the rapidly moving longitudinally 95 bladed mixing and feeding device, and within the drum each of the blades of the mixing device successively strikes and throws the material in two directions, one at right angles to the axis of the drum and the other at an incline to such direction and toward the discharge end of the drum. The different portions of material carried up to the mixing device at one side of the drum are then struck and thrown back towards the opposite side in crossing lines, with a trend, due to the inclined portions of the blades, toward the discharge end of the drum. It will also be observed that this operation of throwing and crossing the material is varied from blade to blade by reason of the fact that the inclined and straight portions of the blades alternate around a given cross section of the mixing device. 100 105 110

2

Of course it will be understood that the materials are mixed not in a wet state but in a dry or merely moist condition so that there is little or no adherence of the particles of material to each other.

5 What I claim and desire to secure by Letters Patent is:

1. In a machine for mixing materials for concrete or the like, a rotatable mixing and feeding device comprising a plurality of blades arranged in circular succession about their axis of rotation, the adjacent blades in circular succession being at an angle to each other with alternate blades substantially parallel to the axis of rotation.
- 10 2. In a machine for mixing materials for concrete or the like, a rotatable mixing and feeding device comprising a plurality of blades arranged in circular succession about their axis of rotation, each of said blades being substantially parallel to said axis for a portion of its length, the remaining portion of the blade being at an angle to said axis, the angular portion of each blade being opposite to 15 said parallel portion of its adjacent blade.
- 15 3. In a machine for mixing materials for concrete or the like, the combination of a drum, a mixing and feeding device therein comprising a shaft and a series of circularly arranged blades thereon, the adjacent blades of the series being arranged at an angle to each other, said shaft having 20 its axis parallel to the axis of the drum and eccentrically therein, and means for revolving said mixing and feeding device to cause the blades to successively engage the materials to be mixed.
- 25 4. In a machine for mixing materials for concrete or the like, the combination of a drum, a mixing and feeding device therein comprising a shaft and a series of circularly arranged blades thereon, the adjacent blades of the series being arranged at an angle to each other, said shaft having 30 its axis parallel to the axis of the drum and eccentrically therein, and means for revolving said mixing and feeding device to cause the blades to successively engage the materials to be mixed.

its axis parallel to the axis of the drum and eccentrically 35 therein, and means for rotating the mixing and feeding device and the drum in contrary directions.

5. In a machine for mixing materials for concrete or the like, the combination of a rotatable drum, a mixing and feeding device therein comprising a shaft and a series of 40 circularly arranged blades thereon, the adjacent blades of the series being arranged at an angle to each other, said shaft having its axis parallel to the axis of the drum and eccentrically therein, and means for rotating the mixing and feeding device in a contrary direction to and at a 45 greater speed than the drum.

6. In a machine for mixing materials for concrete or the like, the combination of a rotatable drum, a rotatable mixing device therein having a circular series of flat blades extending practically continuously from end to end of the 50 mixing device and arranged with their faces transverse their path of motion, the mixing device being arranged eccentrically and longitudinally within the drum, and means for rotating the drum and mixing device in contrary directions.

7. In a machine for mixing materials for concrete or the like, the combination of a rotatable drum, a rotatable mixing device therein having a circular series of flat blades extending practically continuously from end to end of the 55 mixing device and arranged with their faces transverse their path of motion, the mixing device being arranged eccentrically and longitudinally within the drum, and means for rotating the mixing device in a contrary direction and at a greater speed than that of the drum.

In testimony whereof I affix my signature, in presence of 60 two witnesses.

WILLIAM H. PETERS.
